CLAIM

I claim the ornamental design for an angular LED light fixture, as shown and described.

DESCRIPTION

FIG. 1 is a perspective view of an angular LED light fixture. FIG. 2 is a right side elevation view of the angular LED light fixture of FIG. 1.

FIG. 3 is a left side elevation view of the angular LED light fixture of FIG. 1.

FIG. 4 is a front elevation view of the angular LED light fixture of FIG. 1.

FIG. 5 is a rear elevation view of the angular LED light fixture of FIG. 1.

FIG. 6 is a top plan view of the angular LED light fixture of FIG. 1; and,

FIG. 7 is a bottom plan view of the angular LED light fixture of FIG. 1.
